UNITED STATES PATENT OFFICE.

JACOB G. SLATER, OF POUGHKEEPSIE, NEW YORK, ASSIGNOR OF ONE-HALF
TO JOHN P. WILSON, OF SAME PLACE.

CAR-COUPING.

SPECIFICATION forming part of Letters Patent No. 340,681, dated April 27, 1886.

Application filed February 20, 1886. Serial No. 192,645. (No model.)

To all whom it may concern:

Be it known that I, JACOB G. SLATER, a citizen of the United States, residing at Poughkeepsie, in the county of Dutchess and State 5 of New York, have invented certain new and useful Improvements in Car-Couplers; and I do hereby declare the following to be a full, clear, and exact description of the invention, such as will enable others skilled in the art to 10 to which it appertains to make and use the same.

My invention relates to car-couplers; and it consists in the construction and arrangement of the parts, which will be more fully herein-after described, and pointed out in the claims.

15 The object of my invention is to provide a car-coupler, specially adapted for use on freight-cars, which shall be simple in its construction, readily and easily handled and operated, and cheaply manufactured. I attain 20 these objects by the construction of coupler illustrated in the accompanying drawings, wherein like letters and figures of reference indicate similar parts in the several views, and in which—

25 Figure 1 is a perspective view of my improved car-coupler. Fig. 2 is a longitudinal vertical section of the same with the pin in a locking position. Fig. 3 is a view similar to Fig. 2 with the pin in a position to release 30 the link. Fig. 4 is a detail view in elevation of the link-pin.

A represents a draw-bar having a draw-head, B, on the front portion thereof, as in the usual form of construction now in use. The 35 head B has a projection, B', on the top thereof, said projection having a longitudinal slot, b, therein which, as seen in Fig. 1, has two transverse slots, b' b', at right angles thereto. The slot b extends downward through the 40 draw-head B, narrowing as it reaches the bottom thereof.

The slots b', as they appear in Fig. 1, are 45 openings to the camway C. This camway C consists of an inclined narrow curve, 1, at the upper portion thereof, and the said camway broadens, having a straight wall, 2, on one side terminating in a recess, 3, at an angle to 50 said wall 2, and the opposite side of the way has an inclined wall, 4, which runs down by another inclined wall, 5, of a different angle,

and unites with the recessed way 3. The slot b passes vertically through the head B, as heretofore described, and on its front wall is provided with a projection, 6, and indentations 77.

The link-pin D is substantially of the form 55 illustrated in Fig. 4, having a reduced portion, d, in the upper portion, which is provided with a handle, as d', and wide portion d' in the lower portion thereof, terminating on an incline to a rounded point. The front portion of this draw-pin D is provided with indentations 88 and a projection, 9. The lower indentation is formed with a shoulder, 10, which engages with a like shoulder, 11, formed in the front portion of the vertical slot b in 65 draw-head B. This link-pin D is also provided with wrist-pins d'', which engage with the camway C, formed in the draw-head, said pins d'' extending outwardly from each side of the link-pin D near the lower portion there- 70 of.

When the link-pin D is inserted through the longitudinal slot b, the wrist-pins d'' there-in enter the transverse slots b' and pass through the curved narrow portion 1 of the camway 75 C, thence into the widened portion of the said camway, and when in a position to lock the link-pin D in position the said wrist-pins ride down the walls of the said widened camway and drop into the recess, all of which is shown 80 in Fig. 2.

As seen in Fig. 3, the link-pin is tilted back on an incline, and the wrist-pins move up the inclined wall of the camway.

When the link-pin is dropped into the position as heretofore described, the indentations and projections on the link-pin engage with the indentations and projections in the front part of the head B, and any tendency to a displacement of the link-pin when in a vertical position by a sudden jarring of the car is prevented by the interlocking of the said parts.

The link-pin D is also somewhat widened at or about the point where the greatest indentation occurs, by making the back of the said pin slightly curve outward, bringing the strain upon this re-enforced portion of the pin.

The ordinary form of link, as E, is used in 100

connection with my improved form of coupler, necessitating no departure from the construction of the ordinary form of coupler now used.

5 In coupling cars with my improved coupler attached thereto the link E slides into the opening of the draw-head B, and strikes against the inclined foot portion of the link-pin D, and it then automatically rises and allows the link to pass under it, and then drops by gravity through the link, and adjusts itself relatively to the indentations and projections and the wrist-pins thereon to the camways. In uncoupling the cars the said link-pin D is pushed backward, as seen in Fig. 3, and the link E allowed to automatically free itself from securement by the said link-pin.

On no occasion will the link-pin withdraw itself from its slot. It is always in the slot 20 and ready for coupling, and cannot be jolted or jarred out of its relative position in said slot. When the cars are coupled, or when jolting or jarring takes place, the link-pin always assumes such a position as to automatically drop by gravity back to its normal locking position. It will be observed that all of 25 the curves in the indentations, projections, and camway-walls are formed smooth, and gradually change from one curve to the other, thus overcoming any tendency to a cramping 30 of the link-pin, which would result were the said curves sharp and of uneven gradation.

The link-pin, when forced from its normal locking position, is prevented from entire dis- 35 placement from the draw-head by its wrist-pins entering the enlarged portion of the camway C and striking against the upper wall thereof, which will prevent it from passing entirely out, as the way formed at this point 40 is a compound curve, and the distance between the walls thereof being only of such width as to allow the wrist-pins to pass through. The said link-pin can only be removed, when desired, by pushing it back and drawing the 45 wrist-pins up through the way 1, and it is a matter of impossibility to remove the link-pin from its intended position by any other means.

In accidents on railways the cars often assume such a position as to cramp the link, so 50 that it is rendered immovable, and consequently a great loss of property by fire or otherwise is the result. By the use of my coupling the link may assume any position and 55 still be readily uncoupled.

By the use of my improved coupler no aid is needed in assisting it to operate, as it automatically couples of itself and assumes its normal locking position. By this means no at-

tendant is necessary and liable to danger, the 60 only aid required being when it is desired to uncouple the cars, when the link-pin is suitably pushed back to allow the link to draw out. By this attention no danger is incurred, as the 65 cars separate one from the other. In uncoupling and coupling the cars an auxiliary can be used in the form of a chain or cord attached to the upper portion of the link-pin, and be carried or held in any convenient position for 70 operation.

The draw-head B, with its slots and camways, may be cast or constructed in any suitable manner and of any kind of metal adapted to 75 the purpose.

It is obvious that many minor details in the 75 construction and arrangement of the parts may be made and substituted for those shown and described without in the least departing from the nature and principle of my invention.

Having thus described my invention, what 80 I claim as new, and desire to secure by Letters Patent, is—

1. In a car-coupler, the combination of a draw-head having a vertical longitudinal slot therethrough provided with indentations and 85 projections at the front end thereof and transverse slots about midway of the vertical longitudinal slot recessed into the sides thereof and forming camways, a link-pin having wrist-pins or gudgeons on either side thereof, and 90 projections and indentations on the front part thereof, corresponding to the indentations and projections in the front end of the vertical longitudinal slot, substantially as described.

2. In a car-coupler, the combination of a 95 draw-head having a rib on the upper portion thereof, and provided with a vertical longitudinal slot and vertical transverse slots through said rib and head, said vertical longitudinal slot having projections and indentations at the 100 front end thereof, and the transverse slots being recessed in such shape as to form camways, a link-pin having projections and indentations on the front part thereof corresponding to the indentations and projections at the front 105 end of the vertical and longitudinal slot, whereby said link is prevented from rising up when in place, and also wrist-pins or gudgeons to carry said link-pin up and down the camways out of and into place where the 110 coupler is used, substantially as described.

In testimony whereof I affix my signature in presence of two witnesses.

JACOB G. SLATER.
